UNITED STATES PATENT OFFICE.

GEORGE HAVELL, OF NEWARK, NEW JERSEY, ASSIGNOR TO THE HAVELL MANUFACTURING COMPANY, OF SAME PLACE.

DESIGN FOR A BICYCLE-LAMP BODY.

SPECIFICATION forming part of Design No. 26,177, dated October 13, 1896.

Application filed May 22, 1896. Serial No. 592,681. Term of patent 14 years.

To all whom it may concern:

Be it known that I, GEORGE HAVELL, a citizen of the United States, residing at Newark, county of Essex, State of New Jersey, have invented a certain new and useful Design for a Body for Bicycle-Lamps, fully described and represented in the following specification and the accompanying drawings, forming a part of the same.

10 This design relates to a bicycle-lamp body, to the bottom portion of which an oil-cup is commonly secured detachably.

The design is illustrated in the annexed drawings, in which—

15 Figure 1 is a perspective view of the lamp. Fig. 2 is a front elevation of the same, and Fig. 3 is an edge view.

The central portion of the body is of octagonal prismatic shape, the eight corners of 20 the prism being horizontal. The ends of the prism are terminated by flat annular portions, from the inner edges of which short cylindrical portions are projected outward

and terminated by convex faces. A smoke-funnel of flaring shape is projected from the 25 top of the body and a cylindrical collar is projected from the bottom of the body.

The essential feature of the design is the lamp-body shaped as a horizontal octagonal prism, with annular flat ends having short 30 cylinders projected therefrom and terminated by convex faces, and provided upon the top with the flaring ends funnel and upon the bottom with cylindrical collar.

Having thus set forth the invention, what 35 is claimed herein is—

The design for the body of a bicycle-lamp, substantially as herein shown and described.

In testimony whereof I have hereunto set my hand in the presence of two subscribing 40 witnesses.

GEORGE HAVELL.

Witnesses:

A. G. WILLIAMS,
THOMAS S. CRANE.
